UNITED STATES PATENT OFFICE.

WILLIAM MANGIN, OF RAYMOND, IOWA.

WINDOW-FASTENER.

1,101,944.

Specification of Letters Patent. Patented June 30, 1914.

Application filed April 8, 1914. Serial No. 830,380.

To all whom it may concern:

Be it known that I, WILLIAM MANGIN, citizen of the United States, residing at Raymond, in the county of Blackhawk and 5 State of Iowa, have invented certain new and useful Improvements in Window-Fasteners, of which the following is a specification.

The present invention relates to certain 10 new and useful improvements in the construction of window fasteners such as are adapted to be applied to the meeting rails of a pair of sashes to prevent opening of the window from the outside of the building by 15 a burglar or unauthorized person.

The object of the invention is to provide 20 a device of this character which is simple and inexpensive in its construction, which can be readily applied to any conventional form of window, which can be easily manipulated and quickly set in either an operative or an inoperative position, and which 25 will securely lock the window sashes together and hold them against relative sliding movement when in an operative position.

With these and other objects in view, the 30 invention consists in certain novel combinations and arrangements of the parts as will more fully appear as the description proceeds, the novel features thereof being pointed out in the appended claim.

For a full understanding of the invention, 35 reference is to be had to the following description and accompanying drawing, in which:—

Figure 1 is a top plan view of a window fastener constructed in accordance with the invention, showing the same as applied to the meeting rails of a pair of sashes. Fig. 2 40 is a transverse sectional view on the line 2—2 of Fig. 1. Fig. 3 is a similar view on the line 3—3 of Fig. 1. Fig. 4 is an enlarged plan view of one end of the base plate.

Corresponding and like parts are referred 45 to in the following description and indicated in all the views of the drawing by the same reference characters.

Referring to the drawing, the numeral 1 50 designates the lower rail of an upper sash A, and the numeral 2 the upper rail of a lower sash B, the two rails 1 and 2 being disposed side by side and in contact with each other, as indicated by Figs. 2 and 3, when the window sashes are in a closed 55 position.

A base plate 3 is applied to one of the

meeting rails, being shown in the present instance as applied to the upper rail 2 of the lower sash B. This base plate is formed with the pendent side flanges 3^a by means of which the body portion thereof is held in a raised position above the rail 2, suitable fastening members such as the screws 4 being provided for securing the base plate in position. A longitudinal slot 5 is formed 60 in one end of the base plate 3, the said slot communicating at one extremity thereof with a laterally disposed curved slot 6.

A locking bolt 7 is slidably mounted upon the top of the base plate 3 and arranged 70 to have both a longitudinally sliding and a laterally swinging movement. A pair of guide pins 8 project downwardly from the locking bolt 7 through the longitudinal guide slot 5 and terminate in heads 9 which 75 operate in the clearance space between the base plate 3 and the top of the rail 2 and engage the lower face of the base plate to prevent the guide pins 8 from pulling through the slot 5. The locking bolt 8 is 80 thus held against the upper face of the base plate 3, although it can have a longitudinal sliding movement thereon as the guide pins 8 move back and forth in the longitudinal slot 5.

One end of the locking bolt 7 is connected by a tension spring 10 to a suitable lug or projection 12 at the end of the base plate 3, while the opposite end of the locking bolt is formed with a laterally projecting returned or hooked end 7^a which is adapted to project over the lower rail 1 of the upper sash A. The nose of the hooked end 7^a is adapted to enter a keeper 13 upon the upper sash, and the spring 10 95 normally tends to slide the locking bolt 7 in such a direction as to retain the hooked end yieldably within the said keeper.

A handle or finger piece 14 is applied to the hooked end 7^a of the locking bolt 7 and 100 by grasping this handle and sliding the locking bolt 7 against the action of the spring 10 the hooked end of the locking bolt can be withdrawn from the keeper 13. Furthermore, when the guide pin 8 remote 105 from the spring 10 reaches the end of the longitudinal slot 5, the said guide pin can be swung laterally into the curved slot 6, thereby swinging the locking bolt 7 about the other guide pin 8 as a center so as to 110 move the hooked end 7^a of the locking bolt laterally away from the keeper 13 and lower

rail of the upper sash. A notch or seat 15 is provided in one side of the curved slot 6 and the guide pin 8 may be brought into engagement with this seat to lock the bolt 7 in an inoperative position against the action of the spring 10. When the locking bolt is in this position the two window sashes are free to slide independently of each other and the window may be opened 10 and closed in the usual manner independently of the sash fastener. However, when it is desired to lock the window, it is merely necessary to bring both of the guide pins 8 into the longitudinal slot 5 so that the spring 15 10 can draw the hooked end 7a of the locking bolt into engagement with the keeper 13 and retain it yieldingly in said position.

Having thus described the invention, what I claim as new and desire to secure by Letters Patent, is:—

A sash fastener including a base plate adapted to be applied to one of the meeting rails of a pair of sashes and formed with a longitudinal slot and also with a laterally

disposed branch slot communicating therewith, a locking bolt slideable upon the base plate, a pair of guide pins projecting from the locking bolt and slideable within the longitudinal slot, a keeper upon the opposite meeting rail of the sashes, the locking bolt being formed with a hooked end adapted to engage the keeper, and a spring engaging the locking bolt to hold it in operative position, said locking bolt being adapted to be moved longitudinally to withdraw the hooked end thereof from the keeper and then swung laterally about one of the pivot pins as a center, the other pivot pin entering the laterally disposed branch slot of the base plate to retain the locking bolt in an inoperative position against the action of the spring.

In testimony whereof I affix my signature in presence of two witnesses.

WILLIAM MANGIN.
